CLAIM

The ornamental design for the mobile device case, as shown and described.

DESCRIPTION

FIG. 1 is a perspective view of the mobile device case, showing multiple puzzle-type lens housings arrayed on the back surface;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an additional perspective view thereof, illustrating the multiple puzzle-type lens housings in an alternate position.
